UNITED STATES PATENT OFFICE

FRIEDRICH DIETZ, OF NUERMBERG, GERMANY

PUMP

Application filed February 27, 1930, Serial No. 431,807, and in Germany April 16, 1928.

My invention relates to pumping devices and more especially to oil-well pumps. It is an object of my invention to provide a pump of this kind which is capable of withstanding 5 the attacks by the mechanical and chemical admixtures of the oil.

To this end I use in the construction of those parts of such pumps which are exposed to these attacks a material, which is able to 10 withstand abrasion and corrosion, but I may also line such parts with a material of this kind.

Pumps for conveying oil from oil-wells are known to undergo rapid wear at the valves, 15 pistons and cylinders so that they require exchanging after comparatively short operation periods. The cause of this excessive wear is partly the fine quartz sand carried along by the oil which, together with the oil, 20 acts like emery, grinding melting surfaces, and partly the corrosion by the liquids admixed to the oil, and containing brine and acids.

It has been attempted to eliminate this 25 wear by using in the construction of the pumps special materials such as steel and bronze alloys, hardened steel and the like, but none of the materials hitherto used will stand abrasion as well as corrosion.

30 The fitting of the pistons in reciprocating pumps, and consequently also the efficiency of the pumps, is reduced by the wear to which the pumps are subjected to such an extent that after comparatively short periods, often

35 after one or two weeks of operation, the output of the pump is altogether out of proportion to the power input and the pumps must be exchanged. This is very expensive not only on account of the cost of the pumps

40 themselves, but also on account of the time and labor required for the exchange which make up a considerable item, as the depth of the wells frequently exceeds 5000-6000 feet. Obviously the well is laid up while the pump 45 is being exchanged which entails another heavy loss.

An attempt to convey oil by rotary pumps has failed altogether notwithstanding the use 50 of the best material, as with the high numbers of revolution of the pistons (about 3000

per min.) the grinding action, even with a low percentage of quartz sand, is much more detrimental than in pumps having reciprocating pistons moving at low speed with impure oil. The life of rotary pumps is sometimes confined to less than one day.

Even if a material were produced which would stand abrasion, there would still be the problem of rendering it proof against corrosion. A material fulfilling these conditions must be harder than quartz and must not be attacked by the chemical action of brine and other chemical impurities in the oil.

I have now found that the carbon compounds of silicon and more especially silicon carbide are better adapted for use in the construction of the wearing faces of cylinders, pistons and valves than any other material hitherto used. The Brinell hardness of 55 silicon carbide or carborundum is 10 while that of quartz is 7. The compound is further proof against the chemical action of the brine and the acids which may be admixed with the oil. On account of its lower degree 60 of hardness quartz cannot exert a grinding action on silicon carbide, and therefore the life of a pump, the working parts of which are made of or lined with silicon carbide, is 65 practically unlimited.

In the drawings affixed to this specification and forming part thereof several parts of a pump embodying my invention are illustrated diagrammatically by way of example.

In the drawings

Fig. 1 is an axial section of a pump,

Fig. 2 is an axial section of a slightly modified piston, and

Fig. 3 is an axial section of a flap valve in which the valve body and the seat are lined 75 with silicon carbide.

Referring to the drawings and first to Fig. 1, 1 is the pump cylinder, 2 is the piston, 3 is the delivery valve at the top of the piston, 80 8 is its seat, 4 is the suction valve with its seat 9, 5 is the piston rod, 6 is a lining covering the cylinder wall, and 7 is a liner in the skirt of the piston. The linings 6 and 7 and the valve seats 8 and 9 are made of silicon 85 90 95 100 carbide.

carbide. The valve bodies 3 and 4 may consist of the same material.

The liner 7 of the piston 2 may be subdivided into a plurality of rings 10 as shown in Fig. 2, this arrangement being generally preferable to a liner made in one piece.

In Fig. 3, 13 is a flap valve which is hinged to a seat 14 at 15. The valve is lined with a plate 11, the seat with a bushing 12, both made of silicon carbide.

While I have specifically referred to silicon carbide or corborundum as being adapted for the purpose of this invention, obviously other materials having similar properties, for instance other carbides of great hardness and high resistivity against corrosion may be used to replace it. In all cases a binder of ceramic character or a metallic binder may be used in the moulding of the parts in question.

I wish it to be understood that I do not desire to be limited to the exact details of construction shown and described for obvious modifications will occur to a person skilled in the art.

In the claims affixed to this specification no selection of any particular modification of the invention is intended to the exclusion of other modifications thereof and the right to subsequently make claim to any modification not covered by these claims is expressly reserved.

I claim:

1. Pumping device comprising a piston the working surface of which consists of silicon carbide.
2. Pumping device comprising a piston and cylinder the working surfaces of which consist of silicon carbide.
3. Pumping device comprising a cylinder lined with silicon carbide.
4. Pumping device comprising a cylinder and piston lined with silicon carbide.
5. Pumping device comprising a piston and rings of silicon carbide on said piston.
6. Pumping device comprising a valve partly consisting of silicon carbide.
7. A pump for fluids containing sand and the like, comprising parts constructed of carbon compounds of silicon having a hardness greater than that of said sand, the said parts being such as are subjected to mechanical wear from said sand.
8. The pump of claim 7 in which the carbon compound used in the construction of said parts is silicon carbide.

In testimony whereof I affix my signature.

FRIEDRICH DIETZ.
